John Burt

by his Atty. W. L. Sprague

UNITED STATES PATENT OFFICE.

JOHN BURT, OF DETROIT, MICHIGAN.

CHARCOAL-FURNACE.

SPECIFICATION forming part of Letters Patent No. 276,222, dated April 24, 1883.

Application filed October 25, 1882. (No model.)

To all whom it may concern:

Be it known that I, JOHN BURT, of Detroit, in the county of Wayne and State of Michigan, have invented new and useful Improvements in Charcoal-Furnaces; and I hereby declare that the following is a full, clear, and exact description thereof, reference being had to the accompanying drawings, which form a part of this specification.

- 10 The nature of this invention relates to certain new and useful improvements in the construction of furnaces and retorts for the reduction of wood or peat to charcoal by what is known as the "destructive distillation process," 15 whereby the result sought to be attained is performed with economy and certainty, and whereby the waste heat of the fire employed is utilized for generating steam to run an engine, which may be required at the works.
- 20 The invention consists in the peculiarities of the construction of the parts, their combinations, and operation, as more fully hereinafter described.

Figure 1 is a perspective view of one of my 25 improved devices, showing the front and one side, the opposite end and side being identical with the front and side shown in construction. Fig. 2 is a top plan view, with the top of the furnace and the retorts removed. Fig. 30 3 is a central longitudinal vertical section of the same.

In the accompanying drawings, which form a part of this specification, A represents a shell, made, as preferred, of cast or malleable 35 metal.

B represents a heating-chamber of an elliptical form, (shown by black lines in Figs. 2 and 3,) standing centrally between the two sides of the shell, so as to present one side of the ellipse to the front and the other to the rear, whereby the retort-chambers C are formed—one in front and the other in rear of the elliptical-shaped heating-chamber. This heating-chamber may be cast in two or more pieces, which, when put 40 together at their edges, form the elliptical chamber, or in one piece, if preferred, and the shell is constructed with grooves or slides a, which will receive and embrace the points b of the chamber, so that in case of damage to 45 said chamber it may be removed by hoisting it out, and be replaced by new castings. In

this there is secured a steam-generator, E, which may project into the heating-chamber and above its top, or may project its entire length into such heating-chamber, if preferred, 55 and a flue, F, through the center of said boiler forms the necessary exit-flue to the heating-chamber. The generator E, being cylindrical, leaves a space on opposite sides thereof, as shown in Fig. 2, which is filled in at the top 60 by the cover D. (See Fig. 1.) Each of the retort-chambers C is provided with a hinged or swinging cover, H. The bottoms or floors I of these retort-chambers are inclined from the rear of each chamber to the front, as shown, 65 and in a downward prolongation, J, at the front and rear of the shell are doors K, through which the contents of the retorts are removed from time to time. Beneath these floors and below the bottom of the main body of the shell 70 is the fire-box L, provided with the usual feed and draft doors.

In practice the retorts C are filled with the wood or peat to be treated and the covers of such retorts closed tightly, as well as the doors 75 K at the bottom of such retorts. The boiler E is filled, or partially so, with water, and this boiler is provided with the ordinary apparatus, by means of which water is forced into and the steam taken from such boilers, and it 80 is also provided with a safety-valve that is of the usual construction, and which it is unnecessary to describe. Fire is made in the fire-box, and is governed in the ordinary way of controlling the combustion in fire-boxes. The 85 top of the fire-chamber, being formed partially by the inclined floors of the retorts, presents surfaces against which the flame and heat impinge, and by which such flame and heat is carried into the heating-chamber B. In furnaces for this purpose it has been found that the material under treatment would be charred or converted into coal at or near the top of the retort before it was so converted at the bottom, owing to the natural tendency of the 90 heat to rise, so that the top of the retort would be exposed to the greater heat. Hence the great value in my construction of putting the boiler into the top of the heating-chamber is that it may, by absorbing the higher caloric 100 at that point, render the operation or conversion in the retort more equal during its entire

length. When the material in the retort has been converted the doors K are opened to discharge the coal into suitable carts or receptacles placed under the doors for that purpose, and after being filled they are removed. In order to prevent too much or too sudden contraction or expansion of the parts by the sudden cooling off by withdrawing the fire, a pyramid or pile of brick or other suitable substances may be built up from the fire-bed into the heating-chamber, which, under the action of the fire, will become very highly heated, so that on withdrawing the fire such pile will have stored sufficient caloric to prevent the too rapid cooling down of the parts. If it is desired to save the gas arising from this process of destructive distillation in the retort-chambers for conversion into wood-alcohol or other chemical substances, a suitable pipe or outlet may be provided for that purpose.

What I claim as my invention is—

1. In a charcoal-furnace, the combination of the oblong furnace A and the removable heating-chamber B, arranged to make a division 25 in said furnaces, thus forming retorts C C on each side of said chamber, substantially as set forth.
2. In an oblong charcoal-furnace, the combination of the removable heating-chamber B, 30 arranged in said furnace, substantially as de-

scribed, forming retort-chambers, the floors of which overhang the front and rear of the fire-chamber and incline from the centrally-located heating-chamber to the front and rear to form the top of the front and rear ends of the 35 fire-chamber, as set forth.

3. In a charcoal-furnace, the combination of the heating-chamber B, arranged in the furnace A, forming retorts C C, and provided with a fire-box, with a steam-generator in the 40 top of said heating-chamber, through which the flue of said heating-chamber passes, substantially as described.

4. A charcoal-manufacturing furnace consisting of an oblong-shaped shell, A, provided 45 with grooves or slides a, an elliptically-shaped heating-chamber adapted to engage with said grooves, whereby the retort-chambers C are formed, one on each side of said heating-chamber, a steam-generator, E, through which passes 50 the stack F, located in the upper part of the heating-chamber, a fire-box, L, situated below the inclined floors of the retorts, the parts, with their tops, covers, and doors, being constructed, combined, and operating substantially as and for the purposes specified.

JOHN BURT.
